(57) **CLAIM**

The ornamental design for a flask, as shown and described.

DESCRIPTION

FIG. 1 is a front, left perspective view of the flask showing my new design;

FIG. 2 is a front view thereof, the rear view being a mirror image thereof;

FIG. 3 is a left side view thereof, the right side view being a mirror image thereof;

FIG. 4 is a top plan view thereof; and,

FIG. 5 is a bottom plan view thereof.

The broken lines shown in the drawings are included for the purpose of illustrating environmental structure and form no part of the claimed design.
